UNITED STATES PATENT OFFICE.

FRANK J. ARNEY, OF NEW YORK, N. Y.

DETACHABLE SHIRT-CUFF.

1,254,565.

Specification of Letters Patent. Patented Jan. 22, 1918.

Application filed July 7, 1917. Serial No. 179,201.

To all whom it may concern:

Be it known that I, FRANK J. ARNEY, a citizen of the United States, and a resident of the city of New York, borough of the Bronx, in the county of Bronx and State of New York, have invented a new and Improved Detachable Shirt-Cuff, of which the following is a full, clear, and exact description.

10 The object of the invention is to provide a new and improved detachable shirt cuff arranged securely to hold the cuff accurately in position on the shirt sleeve and giving it the appearance of a cuff permanently attached to the sleeve. A further object is to dispense with buttons on the shirt sleeve and to permit the user to conveniently place the cuff in position on the sleeve and to secure it in place and close the sleeve by the use 20 of a cuff button.

In order to accomplish the desired result, use is made of a shirt sleeve provided with a sleeve band having forwardly projecting loops, a cuff provided with buttonholes 25 adapted to register with the said loops, and a single cuff button engaging the said buttonholes and loops to attach the cuff to the said sleeve and close both the cuff and the sleeve band.

30 A practical embodiment of the invention is represented in the accompanying drawings forming a part of this specification, in which similar characters of reference indicate corresponding parts in all the views.

35 Figure 1 is a plan view of the end of a shirt sleeve and cuff, both shown in open disassembled position;

Fig. 2 is a similar view of the same showing the cuff and the sleeve assembled and 40 with the cuff button engaging one of the buttonholes in the cuff and a corresponding registering loop;

Fig. 3 is a front end view of the cuff attached to the sleeve;

45 Fig. 4 is a cross section of the cuff and sleeve on the line 4—4 of Fig. 2;

Fig. 5 is a similar view of the cuff on the line 5—5 of Fig. 1; and

Fig. 6 is a front edge view of a portion 50 of the cuff and sleeve in closed position.

The forward end of a shirt sleeve 10 is provided with a sleeve band 11 and with the usual split 12 extending lengthwise of the forearm portion of the sleeve. The body 14 of the cuff is made of superimposed outer and inner plies 15 and 16 fastened together

along the margins by the usual stitches 17. On the inner ply 16 of the cuff body are arranged diagonally disposed retaining bands 18 and 19 extending from the sides of the 60 cuff body forwardly, as plainly indicated in the drawings. The outer ends of the retaining bands 18 and 19 extend between the plies 15 and 16, and are secured thereto by the 65 stitches 17, previously mentioned. The forward ends of the retaining bands 18 and 19 extend under and are secured to a band 20 extending lengthwise on ply 16 and secured thereto by stitches 21 and 22, of which the 70 stitches 21 also serve to fasten the forward ends of the retaining bands 18 and 19 in position. By the arrangement described the retaining bands 18 and 19 are disconnected from the inner ply 16 intermediate the ends of the said bands 18 and 19 to permit of 75 passing the ends of the shirt sleeve band 11 under the said retaining bands, as plainly indicated in Fig. 2. Immediately in front of the retaining bands 18 and 19 are arranged buttonholes 25 and 26 extending 80 through both plies 15 and 16 and disposed parallel with the band 20 adjacent the inner edge thereof, as will be readily understood by reference to Figs. 1 and 2. The sleeve 85 band 11 is provided on its forward edge with loops 27 and 28 adapted to register with the buttonholes 25, 26 on placing the sleeve band 11 in position under the retaining bands 18 and 19, as plainly shown in Fig. 2. When the loops 27 and 28 are in registering position with the buttonholes 25 and 26 then the usual cuff button 29 is engaged with the 90 said registering buttonholes and loops 25, 27 and 26, 28 to close the sleeve band 11 and the cuff body 14 and to hold securely the 95 cuff in locked position on the sleeve band 11, as will be readily understood by reference to Fig. 3.

From the foregoing it will be seen that by the arrangement described, the buttons and 100 buttonholes are dispensed with as far as the band 11 is concerned, and by extending the sleeve band 11 under the retaining bands 18 and 19, the cuff is firmly held in place on the sleeve and is securely locked thereto as soon as the user has engaged the cuff button 29 with the registering buttonholes and loops 25, 27 and 26, 28.

Having thus described my invention, I claim as new and desire to secure by Letters 110 Patent:—

1. In combination, a shirt sleeve provided

- with a sleeve band having forwardly projecting loops, a cuff provided with retaining bands under which the sleeve band is to be passed and in front of the bands with buttonholes adapted to register with the said loops, whereby a single cuff button may engage the said buttonholes and loops to attach the cuff to the shirt sleeve and to close both the cuff and the sleeve band.
- 10 2. In combination, a shirt sleeve provided with a sleeve band having button receiving openings, and a cuff having retaining means under which the sleeve band is adapted to be passed and having buttonholes in front of the retaining means and registering with the openings of the sleeve band, whereby provision is made for securely holding the cuff in position on the sleeve band and the latter closed by a cuff button.
- 15 3. A cuff having a multi-ply cuff body provided on the inner face of the innermost ply with diagonally disposed retaining bands extending from the sides of the cuff

toward each other and forward, the retaining bands being attached at the ends to 25 the cuff body and being free of the inner face of the cuff body intermediate the attached ends, and buttonholes formed on the cuff body in front of the forward edges of the said retaining band.

30 4. A cuff having a multi-ply cuff body provided on the inner face of the innermost ply with diagonally disposed retaining bands extending from the sides of the cuff toward each other and forward, the retaining bands being attached at the ends to the cuff body and being free of the inner face of the cuff body intermediate the attached ends, buttonholes formed on the cuff body in front of the forward edges of the said 35 retaining band, and a longitudinally extending band overlying the forward ends of the said diagonal retaining bands and secured to the cuff body.

FRANK J. ARNEY.
